LAMP

Roland C. Walker, New York, N. Y.

Application November 6, 1952, Serial No. 22,173

Term of patent 7 years

(Cl. D48—20)

To all whom it may concern:

Be it known that I, Roland C. Walker, a citizen of the United States, residing at New York, in the county of New York and State of New York, have invented a new, original, and ornamental Design for a Combination Mirror and Photo Night Lamp, of which the following is a specification, reference being had to the accompanying drawing, constituting a part hereof.

Fig. 1 is a top plan view of a combination mirror and photo night lamp, showing my new design;

Fig. 2 is a front elevational view thereof;

Fig. 3 is a side elevational view thereof; and

Fig. 4 is a front perspective view.

The dominant features of my design are shown in solid lines.

I claim:

The ornamental design for a combination mirror and photo night lamp, substantially as shown and described.

ROLAND C. WALKER.
